UNITED STATES PATENT OFFICE.

FRED G. SCHWEISTHAL, OF CHICAGO, ILLINOIS, ASSIGNOR TO STEWART-WARNER SPEEDOMETER CORPORATION, OF CHICAGO, ILLINOIS, A CORPORATION OF VIRGINIA.

VALVE-SNAP ACTION.

Application filed November 21, 1924. Serial No. 751,205.

The purpose of this invention is to provide an improved construction, particularly for embodiment in a vacuum fuel feed device for increasing the certainty of the action of the float for breaking the suction hold on the valve or valves. It consists in the elements and features of construction shown and described, as indicated in the claims.

10 In the drawings:

Figure 1 is a vertical axial section of a vacuum fuel feed tank having the valve operating connections from the float embodying this invention.

15 Figure 2 is a partial view, similar to Fig. 1, of the operating parts of the device, the same being shown in a different position.

20 Figure 3 is a detail section at the line, 3-3, on Figure 1, showing the valve snap action in plan view.

Figure 4 is a sectional view similar to Fig. 2, showing modified form of the invention.

25 Figure 5 is a section similar to Figure 2 showing another modification.

In the structure shown in the drawings 1 is the main or outer tank member; 2 is the inner tank member or vacuum chamber; 3 is the liquid inlet to the vacuum chamber; 30 4 is the outlet valve from the vacuum chamber to the main chamber; 5 is the suction connection to the vacuum chamber; 6 is the air connection to the vacuum chamber; 7 is the suction controlling valve; 8 is the air controlling valve. The snap action for operating the valves from the float, A, comprises the customary levers, 9 and 10, having fulcrum-in-common at 11, and their remote ends connected by the snap springs, 12, the lever, 9, being connected by a link, 13, with the float-connected lever, 14, which has a fulcrum at 15, fixed with respect to the vacuum chamber wall, and which is pivotally connected at 16, with the float stem, 17. The valves, 7 and 8, have the customary loose pivotal connection with the lever, 10, adapting them to be operated by the snap action and to accommodate themselves to their seats by the freedom of their connection with the lever, 10, as mentioned. It will be understood that the levers, 9 and 10, have the usual cross bars, 9^a and 10^a, at their remote ends for attaching the opposite ends of the springs, 12, which are dupli-

cated in the well understood manner and for 55 the well understood reason for permitting the springs to pass the fulcrum of the levers in the snap action.

In the well understood operation of this familiar valve snap action, when the float, 50 rising with the rising level of the liquid in the vacuum chamber, carries the springs past the fulcrum line, causing the upward snap to occur, the lever, 10, which engages between the stops, 8, 8^a, of the stem of the valve, 8, is snapped up against the upper stop, 8^a, and operates by virtue only of the stress of the spring and with the force due only to the tension to which the spring has been subjected in being carried past the fulcrum, 11, for breaking the air valve, 8, away from its seat against the suction tending to hold it seated. In cases of extreme suction, the reaction of the spring may not be 70 sufficient to overcome the suction hold on the valve. In the construction shown, however, the extension, 14^a, of the lever, 14, beyond its pivotal connection with the float stem being in the vertical plane of thrust of the valve, 8, and extending under the lower end of the valve stem and deriving from the upward movement of the float a vertical movement of about twice that of the float, is caused to strike the lower end of the stem of the valve, 8, a quick blow when the snap action occurs, thus overcoming the suction hold on the valve and insuring its opening when the snap action occurs under circumstances which might prevent its opening in 75 the absence of said lever extension.

80 While the extension, 14^a, of the lever, 14, is particularly effective because its extended portion travels farther and faster than the float itself, this multiplication of movement is not essential to the result. Figure 4 shows a slightly modified construction in which the lever, 14^a, corresponding to lever, 14, does not extend beyond its pivotal connection with the float, A, but instead, the float carries a boss, 18, and the stem of the valve, 8, is extended downward as seen at 8^c for encounter with the boss, 18, as the float approaches the upper limit of its movement. The snap action of course accelerates this final portion of the float movement and causes it to strike a direct blow upon the extension, 8^a, for unseating the valve, 8. If 85 desired instead of extending the valve stem 100 105

downward an auxiliary stem, 19 may be mounted on the float, A, in a supporting boss, 20, as shown in Figure 5, this stem, 19, being aligned with the stem of the valve, 8, so as to encounter the lower head or stop, 8^b, and dislodge the valve from its seat as the float is snapped upward at the limit of its travel.

I claim:—

10. 1. In a device for the purpose indicated in combination with a chamber having liquid inlet and outlet and having a fluid pressure connection at the upper part, a valve controlling said fluid pressure connection; a float adapted to move with the change of level of the liquid; a snap action connection between the valve and the float comprising a pivoted lever pivotally connected with the float and extended from the float pivot in a plane for encounter of its extension with a valve-connected part in the snap movement whereby the snap action causes the lever extension to strike a blow for displacing the valve from its seat.
15. 2. In a device for the purpose indicated, in combination with a chamber having liquid inlet and outlet and having a suction connection for producing partial vacuum above the liquid and an atmosphere connection for defeating such partial vacuum, a valve controlling the air connection; a float adapted to move with the change of level of the liquid, a snap action connection between the valve and the float, comprising a lever pivotally connected with the float and extending a free end portion from said pivotal connection in a plane for encounter of said extension in the snap movement with a valve-connected part, whereby the lever extension is caused to strike a blow for breaking the suction hold on the air valve in the movement of the float due to the rise of the liquid level.
20. 3. In a device for the purpose indicated, in combination with a chamber having liquid inlet and outlet and having a fluid pressure connection at the upper part, a valve controlling said fluid pressure connection; a float adapted to move with the change of level of the liquid; a snap-over device connected with the float and means connected with the snap-over device for striking the

valve in the direction for displacing it from its seat, having in the snap an extended range of movement for acquiring momentum before it encounters the valve. 55

4. In a device for the purpose indicated, in combination with a chamber having liquid inlet and outlet and having a fluid pressure connection at the upper part, a valve controlling said fluid pressure connection, a float adapted to move with change of level of the liquid, a snap action connection between the valve and the float including a lever pivotally connected to the float and having a free end portion farther from the lever fulcrum than said pivotal connection, whereby said free end has a wider range of travel than the float; said end portion moving in a plane for encounter with a valve-connected part in the snap movement for striking a blow to displace the valve from its seat. 65 70

5. In a device for the purpose indicated, in combination with a chamber having liquid inlet and outlet and having a fluid pressure connection at the upper part, a valve controlling said fluid pressure connection, a float adapted to move with the change of level of the liquid, a snap-over device connected with the float and with the valve designed to accelerate the movement of the float as it approaches its limit of travel and means carried by the float for direct encounter with a valve-connected part in said accelerated movement for displacing the valve from its seat. 75 80 85

6. In a device for the purpose indicated, in combination with a chamber having liquid inlet and outlet and having a fluid pressure connection at the upper part, a valve controlling said fluid pressure connection, a float adapted to move with the change of level of the liquid, a snap-over device connected with the float and with the valve designed to accelerate the movement of the float as it approaches its limit of travel and means positively connected to the float in position for direct encounter with a valve-connected part for striking a blow to displace the valve. 90 95 100

In testimony whereof, I have hereunto set my hand this 19th day of November, 1924.

FRED G. SCHWEISTHAL.
